UNITED STATES PATENT OFFICE.

ALEXANDER D. POLOU BOYARENOK, OF NEW YORK, N. Y.

SHOE-LACE FASTENING.

1,315,860.

Specification of Letters Patent.

Patented Sept. 9, 1919.

Application filed February 13, 1918. Serial No. 216,912.

To all whom it may concern:

Be it known that I, ALEXANDER D. POLOU BOYARENOK, a subject of the Russian Provisional Government, residing at New York, in the county of New York and State of New York, have invented new and useful Improvements in Shoe-Lace Fastenings, of which the following is a specification.

This invention relates to shoe lace fastenings and the like and has for its principal object, the provision of a device of this character which will consist of mating instrumentalities adapted to be respectively associated with the shoe and lace thereof for securing the ends of the latter together and for preventing accidental or casual untying or separation of said ends.

A still further object of the invention resides in the provision of a device of this character which will materially facilitate an adjustment of the lace upon the shoe and for holding the ends of the lace in a neat and attractive position when tied.

With the above and other objects in view which will appear as the nature of the invention is better understood, the same consists in the improved construction and novel arrangements of parts which will hereinafter be fully described and particularly pointed out in the claims.

In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1, is a perspective view of a portion of a shoe showing the application of the invention thereto.

Fig. 2 is a perspective view of the clip showing the retaining plate adjusted to an opened position.

Fig. 3 is a similar view showing the retaining plate closed.

Fig. 4 is a vertical section through the clip.

While the invention is principally designed for use in connection with boots and shoes, I do not wish to limit myself in this connection as it obviously follows that it may be equally as effective and desirable for use in connection with other articles of apparel.

In the specific application of the inven-

tion to boots and shoes, use is made of eyelet members 10, which are arranged in vertical rows upon the uppers of the shoe as illustrated in Fig. 1.

The lace 20 is constructed of any suitable well known flexible material which is adapted to be passed through said eyelet members.

One terminal A, of the lace is provided with a fixed elongated loop 22 while the opposite mating terminal B, of the lace is provided with a clip 23. This clip may be constructed of metal or other suitable well known material which is bent upon itself to provide clamping branches 24 and 25, the lower end of the latter being curved forwardly at 26 and then upwardly at 27 so as to constitute a supporting hook 28. The said portion 27 is spaced for a suitable distance from the branch 25 and adapted to mate with the curved end 29 of said portion 27 is a swinging retaining plate 30, the free end of which being provided with a curved branch 31 which is adapted to overlie the terminal 29. In order to insure an operative retention of the plate 30, against said terminal 29, the branch 26 is provided with a resilient keeper 32 which is adapted to overlie said extension 31 as shown in Fig. 4. Said keeper 32 may be manipulated by hand in order that the retaining plate can be conveniently adjusted to any desired position as will be understood. The upper end of said retaining plate is mounted to swing in hinge fashion from angularly disposed lugs 33-34, formed at the upper end of the clamping section 24. Adjacent to this point, said retaining plate is provided with a foot 35 which is adapted to come in pressing contact with the branch 24 and thereby cause said branch to be moved relatively of the branch 25. Said branch 24 is provided with a horizontal line of projections 36 and a vertical line of similar projections 37. The two branches 24 and 25 which constitute the clamping features of the clip are adapted to straddle the upper of the shoe as illustrated in Fig. 1. When the retaining plate 30 is adjusted to a closed position, it will be observed that the two sections 24 and 25 of the clamp will be brought into clamping impingement with the upper of the shoe and the clip securely maintained in a fixed position.

After the lace has been passed through the respective eyelet members, it is tied in bow

form as shown at C, in Fig. 1. The clip 23 is then brought into engagement with the upper portion of the shoe as above referred to. The retaining plate 30 is then opened 5 and the elongated loop 22 of the lace terminal A, is passed over the extension 27 as clearly illustrated in Fig. 3. The ends of the lace are then maintained in relatively fixed positions upon the shoe so as to positively eliminate accidental untying of the lace while the shoe is worn. If desired, the loops of the bowknot C, can be brought together and also passed over the hook extensions 27 to further safe guard against accidental untying of the lace. The bight 26 10 of the clip is preferably slotted at suitable places 38 to permit the lace terminal B, to be threaded therethrough and the free extremity of said terminal secured as at 39 15 to the mating portion of said terminal as clearly illustrated in Fig. 4.

What is claimed as new is:—

1. A device of the character described comprising a sheet metal body portion 25 formed of flexible material and bent intermediate of its ends to form a plurality of

substantially parallel rectangular members, a hinged closing plate carried by the body portion, and means carried by one of the free ends of the body portion for engagement 30 with the free end of the hinged plate to retain same in closed position.

2. A device of the character described comprising, a substantially S-shaped body portion, a pair of spaced tongues formed on 35 the body portion intermediate of its ends, a hinged closing plate pivotally mounted in said tongues, and means carried by one of the free ends of the body portion, and engaging the hinged closing plate, to maintain 40 the same in closed position.

3. A device of the character described comprising, a substantially S-shaped body portion, a hinged plate carried by the body portion intermediate of its ends, and having 45 a curved free end, and means carried by one end of the body portion and adapted to engage the curved end of the hinged plate to retain the same in closed position.

In testimony whereof I affix my signature. 50

ALEXANDER D. POLOUBOYARENOK.
